CLAIM

The ornamental design for a personal tracking device and strap, as shown and described.

DESCRIPTION

FIG. 1 is a top, left, front perspective view of the personal tracking device and strap.

FIG. 2 is a front view of the personal tracking device and strap.

FIG. 3 is a back view of the personal tracking device and strap.

FIG. 4 is a top view of the personal tracking device and strap.

FIG. 5 is a bottom view of the personal tracking device and strap.

FIG. 6 is a left view of the personal tracking device and strap.

FIG. 7 is a right view of the personal tracking device and strap; and,

FIG. 8 is a bottom, right, back perspective view of the personal tracking device and strap.

The dashed lines are included for the purpose of illustrating portions of the personal tracking device and strap and forms no part of the claimed design.

Sides not shown are either not seen in use or do not bear ornamental features.

1 Claim, 8 Drawing Sheets
